UNITED STATES PATENT OFFICE.

FREDERICK F. HORN, OF COLORADO SPRINGS, COLORADO.

DESIGN FOR A SPOON.

SPECIFICATION forming part of Design No. 21,716, dated July 19, 1892.

Application filed June 10, 1892. Serial No. 438,270. Term of patent 3½ years.

To all whom it may concern:

Be it known that I, FREDERICK F. HORN, a citizen of the United States, residing at Colorado Springs, in the county of El Paso and State of Colorado, have invented and produced a new and original Design for Spoons, of which the following is a specification, reference being had to the accompanying drawing, illustrating the same.

10 The leading feature of my design consists in the shape of the handle and stem by which the bowl and handle are united and which terminates at the one end in a trefoil, which is attached to the bowl and has a socket the edges of which are indented or serrated to receive one end of the handle.

15 Referring to the drawing, A designates the shell-like bowl of a spoon embodying my de-

sign, and B designates the handle thereof. The handle is of the form shown—to wit, tapered from its inner end to its outer end. The inner or larger end of the handle B is merged in a shank C, which is tapered or reduced in size from its outer end toward the bowl A, and the inner smaller end of the shank C terminates in a trefoil D, which is attached to the shell-like bowl A. The upper or outer edge of the shank C is scalloped or indented, forming a finish for the handle.

I claim—

20 The design for a spoon, substantially as herein shown and described.

25 FREDERICK F. HORN.
